UNITED STATES PATENT OFFICE.

ROBERT LIDDELL, OF PUTEAUX, FRANCE, ASSIGNOR TO SOCIÉTÉ PARISIENNE DES PRODUITS DE BEAUTE "GANNA WALSKA," OF PANTIN, FRANCE.

DESIGN FOR A BOX.

Application filed October 3, 1927, Serial No. 23,614, and in France June 3, 1927. Term of patent 7 years.

To all whom it may concern:

Be it known that I, ROBERT LIDDELL, a citizen of the French Republic, residing 11 Rue Michelet, Puteaux, in the Department of the Seine and Republic of France, have invented a new, original, and ornamental Design for a Box, of which the following is a specification, reference being had to the accompanying drawing, forming part thereof.

The figure is a perspective view of a box showing my new design.

This design is characterized by the fact that the cover of the box is ornamented as shown, being divided into two symmetrical parts, differently colored.

I claim:

The ornamental design for a box substantially as shown and described.

ROBERT LIDDELL.
